UNITED STATES PATENT OFFICE.

HERMANN C. G. REMANÉ, OF BERLIN, GERMANY, ASSIGNOR TO GENERAL ELECTRIC COMPANY, A CORPORATION OF NEW YORK.

METALLIC-FILAMENT ELECTRIC INCANDESCENT LAMP.

1,176,602.

Specification of Letters Patent. Patented Mar. 21, 1916.

Application filed October 3, 1912. Serial No. 723,671.

To all whom it may concern:

Be it known that I, HERMANN C. G. REMANÉ, a subject of the Emperor of Germany, residing at Berlin, Germany, have invented certain new and useful Improvements in Metallic-Filament Electric Incandescent Lamps, of which the following is a specification.

The present invention relates to metallic-filament incandescent electric lamps in which the illuminating body is carried back and forth over filament supports of a holder-frame.

Electric incandescent lamps are already known in which the illuminating body is placed zigzag upon the holders which are arranged in two parallel planes on a common supporting stem. Also constructions are known in which the parts of the illuminating body which lie between the holders are clamped in at the supporting parts of the rigid holders or in some other manner are firmly connected with them. If, in the manner usual for illuminating bodies consisting of looped metal filaments, slender elastic holders are used on one supporting ring, and for the holders of the other supporting ring practically non-elastic material is employed, it has been demonstrated that the elastic holders may be strained beyond their limit of elasticity by very severe shocks occurring in the direction of the supporting stem. By this means the elastic holders are so bent that the illuminating body comes out of engagement with the holders over which it is carried.

In order to preserve the elastic holders which cause the sections of the illuminating body to remain stretched rectilinearly during the burning of the lamp, the illuminating body, according to my invention, is interlaced with the practically rigid holders in such a way that forces which are exerted by shocks in an axial direction are taken up by these holders without detriment to the position of the illuminating body or to the elastic supports. This may be attained by interlacing the illuminating body with the rigid holders when applied, as shown in the drawings. Provision is also made which prevents the illuminating body from sliding from the holders.

In the drawing are represented a number of forms of the inventive idea.

55 The simplest solution is shown in Figure 1,

according to which the illuminating body 1 is given one turn about the rigid holder in the curved portions of the hooked ends 2. In the embodiment shown in Fig. 2, the filament is also given one turn around the support and protection against sliding off in the direction of the holder is secured by a dove-tail form 3 in the supporting portion.

In Fig. 3 is shown a construction in which the supporting end of the holder is bent into a helical eye 4. By this arrangement an advantage is secured in that, when axial blows occur, the sections of the illuminating body may be supported not only with relation to the holder itself, but also with relation to the lower curved portion of the helical eye.

In the construction shown in Fig. 4, a curvature 5-5 is provided at both sides of the looped portion where the filament is wound round; this also with a view to further assisting in preventing the illuminating body from slipping off the holder and limiting its longitudinal movement.

In the construction shown in Fig. 5, a projection 6 provided near the end of the holder passes through the turns of the illuminating body to prevent the filament from slipping off the end of the support and limit its longitudinal movement.

In Figs. 6 and 7, holders are represented, which are S-shaped at the ends, by which design the illuminating body is held in position against lateral and longitudinal movement by a sort of weaving, as clearly shown in the drawings.

In Figs. 8 and 9 are represented embodiments in which the illuminating body is interlaced with the individual curvatures in the wave-like ends of the supports similar to a weaving operation. In the embodiment shown in these figures it will be noticed that the filament and the support are so interlaced that the filament has no movement along the axis of the support and only a limited movement in a transverse direction thereto. In this arrangement it is not only possible to so arrange the bent or curved portions of the support that they lie in a plane which passes through the axis of the lamp, but it is also possible to dispose them perpendicularly to the supporting stem or in planes tangential to the embracing ends of the illuminating body.

What I claim as new and desire to secure by Letters Patent of the United States, is,—

1. In an incandescent lamp, the combination of a central supporting stem, a set of hooked flexible supports mounted thereon, a set of comparatively rigid supports mounted thereon, and a continuous filament strung back and forth between said flexible and rigid supports, the rigid supports and the filament being interlaced to limit the movement of the filament toward and from said rigid supports.
2. In an incandescent lamp, the combination of a central supporting stem, a plurality of hooked flexible supports mounted thereon, a plurality of rigid supports mounted thereon, said rigid supports having bent portions, and a filament strung back and forth between said flexible and rigid supports and interlaced with the bent portions of said rigid supports to limit the longitudinal movement of the filament toward and from said rigid supports.
3. In an incandescent lamp, the combination of a central supporting stem, a plurality of hooked flexible supports mounted thereon, a plurality of rigid supports mounted thereon, said rigid supports having bent portions, and a continuous filament strung back and forth between said flexible and rigid supports and interlocked with the bent portions of said rigid supports to prevent undue strain on said flexible supports.
4. In an incandescent lamp, the combination of a central supporting stem, a plurality of hooked flexible supports mounted thereon, a plurality of rigid supports mounted thereon, said rigid supports having bent

portions, and a continuous filament strung back and forth between said flexible and rigid supports, the filament being interlaced with the bent portions of said rigid supports whereby the movement of the filament toward and from the rigid support is limited and undue strain on the flexible support is thereby prevented.

5. The combination in an incandescent lamp of a rigid filament support and a filament interlaced therewith in such a manner as to limit the movement of the filament with respect to the support.

6. The combination in an incandescent lamp of a rigid filament support having a bent portion and a filament interlaced with said bent portion in such a manner as to limit the movement of the filament with respect to the support.

7. The combination in an incandescent lamp of a filament support having a bent portion near the end and a filament interlaced with the bent portion in such a manner as to limit the movement of the filament with respect to the support.

8. The combination in an incandescent lamp of a rigid filament support having a plurality of bends near the end thereof and a filament interlaced with the bent portion in such a manner as to limit the movement of the filament with respect to the support.

In witness whereof, I have hereunto set my hand this 13th day of September, 1912.

HERMANN C. G. REMANÉ.
